Primary Examiner — Jack Reickel

Assistant Examiner — Bobby W Jones, II

(57) **CLAIM**

The ornamental design for a shower head, as shown and described.

DESCRIPTION

FIG. 1 is a perspective view of a shower head, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The dashed or broken lines shown in the shower head in which the design is embodied form no part of the claimed design.

1 Claim, 8 Drawing Sheets
